Corporation, Los Angeles, Calif.
Continuation-in-part of abandoned design application Ser.
No. 134,535, Apr. 15, 1971. This application Oct. 1,
1971, Ser. No. 185,929

Term of patent 14 years

Int. Cl. D9—99

U.S. Cl. D12—53

FIG. 1

FIG. 2

FIG. 3

FIG. 4

FIG. 1 is a perspective view of a plastic pallet showing our new design;

FIG. 2 is an end view of the design shown in FIG. 1;

FIG. 3 is a front view of the design shown in FIG. 1; and

FIG. 4 is a partial perspective of a second embodiment of the plastic pallet of our new design.

The rear of the claimed design is identical to the front shown in FIG. 3. Both ends are identical to the end shown in FIG. 2. The bottom is identical to the top.

The embodiment shown partially in FIG. 4 is identical to the embodiment of FIG. 1 except that each opening of FIG. 1 has the configuration shown in FIG. 4.

It is understood that the pattern shown in FIG. 1 is uniform throughout the top of the new design.

This is a continuation-in-part of application Ser. No. 134,535, filed Apr. 15, 1971, now abandoned.

We claim:

The ornamental design for the plastic pallet, as shown and described.
